UNITED STATES PATENT OFFICE.

WILLIAM H. GATES, OF NEW HAVEN, CONNECTICUT.

COMBINATION SOCKET WRENCH.

Application filed February 4, 1922. Serial No. 534,074.

To all whom it may concern:

Be it known that I, WILLIAM H. GATES, a citizen of the United States, residing at New Haven, in the county of New Haven and State of Connecticut, have invented certain new and useful Improvements in Combination Socket Wrenches; and I do hereby declare the following to be a full, clear, and exact description of the invention, such as will enable others skilled in the art to which it appertains to make and use the same.

This invention relates to a combination socket wrench, and it consists in connecting a socket ratchet head to the socket handle, and utilizing the ratchet head as a receptacle for interchangeable sockets. It further consists in the novel means for detachably connecting the ratchet head to the handle, and the interchangeable sockets to the ratchet head.

Referring to the accompanying drawing:

Figure 1 represents the combined tool carrying an interchangeable socket;

Figure 2 is a detail view of the inner face of the socket handle looking in the direction of arrow *a* of Figure 1;

Figure 3 is a detail view of the ratchet head looking in the direction of arrow *b*, Figure 1;

Figure 4 is a detail view of the opposite face of the ratchet head looking in the direction of arrow *c*, Figure 1;

Figure 5 is a detail broken view partly in section of the assembled ratchet head;

Figure 6 is a broken detail view partly in section of the socket handle;

Figure 7 is a broken view partly in section of the assembled tool and an interchangeable socket connected therewith;

Figure 8 is a detail view of the recessed or socket end of the interchangeable socket looking in the direction of arrow *d*, Figure 7;

Figure 9 is an enlarged broken view of the ratchet teeth and broken view of the pawl connected therewith, and

Figure 10 represents a similar view of the ratchet teeth and pawl, but showing the latter reversed.

The combination tool consists of the handle 1 having the hex recess 2, Figures 2, 6, and 7, formed in the face of the head 3, the split spring stud 4, and the ratchet head 5.

The ratchet head 5 has the hex stem 6 adapted to register with the hex recess 2 of

the handle 1. The hole or opening 7, Figure 3, in stem 6 is a trifle smaller than the split stud of the handle so that the frictional engagement of the split stud with the sides 60 of this opening will prevent accidental displacement of the ratchet head in its workable relation with the handle.

The ratchet head consists of two members, viz: the knurled rotatable member 8, and 65 the base 9 provided with the hex recess 10, see also Figure 7, and the split stud 11. The member 8 is provided with recesses 12, 13, the former to admit a part of the socket member 9, and the latter to receive the stem 70 14 of the member 9. The groove 15 of the stem 14, and the pin 16 maintain the two parts of the ratchet head in workable relation with each other.

The inner surface of the socket member 75 9 is provided with the teeth 17 adapted to be engaged by the spring actuated pawl 18 whose stem 19 extends through the cap 20 located in the outer surface of the member 8, Figure 3. The cap 20 is forked to receive 80 the pawl retaining pin 21.

22 represents an interchangeable socket. In other words, one of the many different sized sockets adapted to embrace the various sizes of nuts or bolt heads. While the hex 85 recess 23, Figure 8, may vary in size and shape in these interchangeable sockets, they will all have a stem of the same size and shape as the hex stem 24 to register with the hex recess 10 of the ratchet head, and each 90 will be provided with an opening similar to the opening 25, Figure 7, for the split stud 11.

The handle rod 26 gives the necessary working leverage for the tool. This rod is 95 longitudinally adjustable so that the tool can engage a bolt head whenever there is room for the tool to rotate.

In operating the tool, the proper interchangeable socket member having been selected and attached thereto, the tool can be rotated right or left by simply changing the position of the pawl 18, Figures 9 and 10.

The advantage of the split stud connection between the handle and ratchet head, and between the ratchet head and the various interchangeable socket members, is that the frictional engagement of these studs will effectually prevent accidental displacement of the several associated members, and they can readily be separated when necessary by an applied force greater than the frictional

engagement of the said studs. Another advantage of these spring studs is that it is not necessary to observe a close fit of the several hexagonal parts, which may be square 5 or of any other angular shape.

Having thus described my invention, what I claim as new is:—

1. A combination socket wrench of the character described, comprising a handle 10 having a socket recessed end, a forked stud located therein, a ratchet head having a stem adapted to be inserted in the recessed end of the handle, said stem having an opening therein adapted to frictionally engage the 15 stud, said ratchet head having a socket recess at its opposite end and a spring pin lo-

cated therein to connect with interchangeable sockets.

2. A combination socket wrench comprising a handle having a recess in one end, a 20 forked stud located therein, a ratchet head comprising a base having a serrated face on one end and a recess on its opposite end, a forked stud within said recess, a rotatable member mounted on the base having a stem 25 adapted to register with the recess of the handle, and means for frictionally engaging the forked stud of said handle, and a reversible pawl engaging the serrated face of the base.

In testimony whereof I affix my signature.

WILLIAM H. GATES.
